GAS STOVE BURNER CONTROL MECHANISM

Richard Besocke, Arcadia, Calif., assignor of
eighty per cent to John P. Frank, Arcadia,
Calif.

Application February 12, 1940, Serial No. 318,507

7 Claims. (Cl. 126—42)

This invention relates to a gas stove burner control device, and is more particularly related to a mechanism adapted to be operatively connected between a burner cover and the gas supply valves to enable the gas supply valves to be locked in closed position except when the cover is raised off of the burner.

Gas stoves as they are now commonly constructed include burner covers which are mounted on the top of the gas stove in such manner as to permit the same to be moved over or to be lowered into position over the gas burners. These covers are generally formed of sheet metal upon which enamel is commonly baked.

When the covers are lowered over the gas burners, they completely close the stove from the top and directly over the burners so that if any one of the burners is ignited, either when the cover is lowered or after the cover has been lowered into position, burning of the cover results with consequent warping of the sheet metal thereof, causing disfigurement and burning of the enamel coating. In addition to this, most gas stoves as they are now manufactured are provided with automatic pilot lights of one character or another which are intended to ignite the gas when the burner valve is open to permit gas to flow through the burner. Should the cover be lowered and the gas valve opened, there results a distinct hazard from this combination of elements, dependent particularly upon the time when the pilot lighting mechanism operates to ignite the gas permitted to flow through the burner. If the pilot light does not operate to immediately light the gas, which often occurs, there is a danger of forming an explosive mixture under the cover which will then be ignited by the pilot with consequent explosion of the said explosive mixture. As most of these stoves are utilized in homes, the danger of opening a gas valve with the cover closed is always present, particularly where there are children or where the stove is mounted in such place that a person passing the stove may strike one of the valve handles to open the same. Even where no actual dangerous results follow, the burning of the gas burner covers so destroys the said covers as to require the replacement of the covers if the appearance of the stove is to be maintained.

It is therefore an object of this invention to provide a mechanism applicable for attachment to stoves or applicable for installation in the stoves as manufactured which will insure that all of the gas valves are closed and remain closed

when the burner cover is moved to position to cover the burners.

Another object of this invention is to provide a mechanism for locking closed the gas valves in all positions of the gas burner cover except its open position.

Another object of this invention is to provide a mechanism for locking closed the gas valves for supplying the gas to gas burners which is so constructed as to prevent lowering of, or moving the burner cover into position over the burners except when the gas valves are all closed.

Another object of this invention is to provide a mechanism adapted for locking all the gas valves of a stove closed which is operatively associated with the burner cover in such manner as to prevent lowering of said cover over the gas burners except when all the gas valves are closed, and which includes a means adapted to hold the cover in elevated position in the event an effort is made to close the said cover over the burners with a gas valve open and which retains the cover in elevated position even when an open gas valve is closed to prevent the cover from dropping into position on the closing of the open gas valve.

Another object of this invention is to provide a mechanism of the class hereinabove set forth which is applicable for mounting in a gas stove as a unit economically and efficiently without requiring material reorganization of the stove and gas control valves or any other part of the stove.

Other objects and advantages of this invention it is believed will be apparent from the following detailed description of a preferred embodiment thereof as illustrated in the accompanying drawings.

In the drawings:

Figure 1 is a perspective view of a gas stove to which the control mechanism embodying my invention has been adapted.

Figure 2 is a sectional elevation taken substantially on the line 2—2 of Figure 1.

Figure 3 is a fragmental elevation of the control mechanism embodying my invention illustrating the same as adapted to a fragment of a stove and showing the mechanism in position with the cover open to permit the gas control valves to be actuated to supply gas to the stove burners.

Figure 4 is a similar view illustrating the retention of the stove cover in elevated position when it is attempted to lower the cover with a valve open.

Figure 5 is a similar view illustrating the clos-

ing of the stove cover when all valves controlling the supply of gas to the burners are closed.

Figure 6 is a sectional view taken substantially on the line 6—6 of Figure 2.

Figure 7 is a sectional view taken substantially on the line 7—7 of Figure 6.

Figure 8 is a sectional view taken substantially on the line 8—8 of Figure 4.

In the preferred embodiment of my invention I have indicated a stove 1 which may be of any suitable or desirable construction or of any of the well known forms now commonly sold. The stove 1 is commonly provided with a multiplicity of burners 2 which, in the present instance, are gas burners spaced apart and controlled by gas valves 3 mounted in the gas supply line 4 to control admission of the gas to the burners 2.

The gas valves 3 commonly have valve stems 5 projecting from the forward face of the stove 1 and having actuating handles 6 secured thereto. One such valve and operating handle is provided for each burner 2.

The stoves as commonly manufactured include a pilot light mechanism generally indicated at 7 whereby gas emitting from each of the burners 2 may be lighted automatically upon opening of its corresponding valve 3.

In order to enhance the appearance of the stoves, and also kitchens in which they are positioned, such stoves are now commonly provided with covers 8 which may be lowered over the upper surface of the stoves 1 and over the burners 2. These covers 8, of which there may be one or more, are connected with the stoves 1 in a multiplicity of different ways and I have not attempted in this application to illustrate the numerous ways in which the covers may be supported with respect to the stoves 1 but for the purpose of illustration have chosen that form wherein the covers 8 are hingedly supported as indicated at 9 at the back of the stove 1. It will be apparent, however, from the hereinafter contained description that my invention is equally susceptible to any other form of mounting of the covers 8 as long as the covers 8 have a movement with respect to the stove 1 so that this movement of the cover may be utilized to actuate the control mechanism embodying my invention.

The control mechanism embodying my invention includes a lock bar 10 which is adapted to be moved into and out of position with respect to all of the burner control valves 3 or their actuating mechanisms so as to prevent opening of these valves 3 except when the cover 8 overlying such burners 2 has been elevated or moved from such overlying position. In the particular form of construction illustrated, the lock bar 10 is shown as including a plurality of locking detents 11 adapted to engage lock pins 12 secured to the valve stems 5. As illustrated, the lock bars 10 are formed with the locking detents 11 formed offset from the face of the locking bars 10 and the locking bar 10 is pivotally supported on pivots 13 carried by brackets 14 secured to the frame or plate element 15 of the stove 1. Thus it will be apparent that when the locking bar 10 is pivoted on the pivots 13, the locking detents 11 will be moved away from position to engage the lock pins 12 carried by the valve stems 5. It will also be apparent that there is only one position of the locking bars 10 in which the locking pins 12 will pass into the locking detents 11 and that there is only one position of the valve stems 5 which is the closed position of the said valves where the lock bar 10 may be rotated to lower the same so

that the pins 12 will pass into the detents 11. The locking bar 10 is adapted to be actuated by an actuating rod 16 pivotally secured thereto as indicated at 17.

5 Means are provided for actuating the rod 16 to move the locking bar 10 to and from locking position and this actuating mechanism is of such an organization and construction as to be of unit construction and of such operation as to have 10 the distinct functions of preventing the lowering of any cover or lid 8 unless the valves 3 controlling the burners 2 which would be covered by that lid are closed; of locking all the said valves 3 closed when the lid 8 is over the burners 2 controlled by the said valves 3 and of preventing dropping of the lids 8 into position when it is endeavored to lower the said lid 8 and it is found 15 the valve 3 is open by the mere closing of the open valve. In order to accomplish these results, 20 the covering mechanism includes a plate 18 which is adapted to support the actuating mechanism as a unit construction, and this plate would then be mounted in its appropriate position upon a frame or plate member 19 of the stove 1 by any suitable securing means as, for example, by means of 25 suitable bolts or the like.

Carried on the plate 18 is control means including a striker bar or lever 20 which is pivotally supported upon the fixed pivot 21. The striker member 20 is yieldably urged by means of a spring 22 into position where it will be engaged by a complementary striking arm 23 actuated by the cover 8 when moved to its open position. In the form illustrated, the striking arm 23 is pivoted at 24 and is connected by a link 25 with the cover 8, so that when the striking arm 23 swings up with the cover, its end engages the edge of the striker lever 20 and pushes this lever into its position illustrated in Fig. 3. This causes rod 16 to withdraw lock-bar 10 from the pins 12, leaving the burner handles 6 free for operation.

The return spring 22 operates to move the striker member 20 and hence the lock bar 10 and its operating rod 16 which is connected thereto, back to the locking position, in which position the parts normally remain except when the striking arm 23 has been engaged by the striker member 20 to move the same against the force exerted by the spring 22 to move the rod 16 to open the lock bar 10, as described above. That is the position indicated in Figure 3. The end of the striking arm 23 is preferably beveled off on its upper edge as shown in the drawings.

The striker member 20 is connected by means of a link 26 with a striking arm or bumper member 27. The stop member or pawl 27 is pivoted on a pin 28 upon the plate 18. The bumper member 27 is a stop pawl and is the means in the combination for engaging end 29 of the striking arm 23 which prevents the lowering of the lid 8 beyond the position as illustrated in Figure 4 when a valve 3 is found open. Thus it will be observed that with the parts in the position as illustrated in Figure 3, that the cover 8 may be lowered to the position indicated in Figure 4 but that when so lowered, the closing of the cover is obstructed, as the bumper member or stop 27 prevents further lowering of the lid 8 if a valve is open, preventing the lock bar 10 moving to locking position. Due to the weight of the cover, the engagement of the engaging end 29 with the bumper arm or stop 27 is sufficient to hold the parts in the position illustrated in Figure 4 against the force exerted by the spring 22 even after the valve handle of every

open valve 3 has been rotated to its closed position, and this would prevent the cover 8 from dropping into closed position. When, however, the cover 8 is raised sufficiently to disengage the end 29 from the bumper bar 27, the spring 22 pulls the striker member 28 and hence through the link 26 of the bumper member 27 to the position indicated in Figure 5, moving the lock bar 16 to the locking position so that the lid may then be lowered over the burner 2.

It will be apparent that as the locking pins 12 are now engaged within the locking detents 11 that no valve 3 can be opened with the cover closed.

It will be noted that the plate 18 is formed with a stop flange 30 which engages the striker arm 23 when the cover 8 is moved to the fully open position beyond its center as determined by the hinge 9. The act of opening the cover 8 to the position indicated in Figure 3 moves the bumper bar 27 into the position to engage the bumper end 29 by causing the striker member 28 to be rotated around its pivot 21 in a direction to throw the bumper member 27 in the path of the engaging end 29 of the striker arm 23.

Having fully described my invention, it is to be understood that I do not wish to be limited to the details herein set forth, but my invention is of the full scope of the appended claims.

I claim:

1. In combination with a stove having a plurality of gas burners, means for supplying gas to the burners including valve members and a cover for closing the stove over the burners, of a control means for controlling the said valves permitting their opening only with the cover in raised position, said control means comprising a multiple lock bar adapted to lock the valves in closed position, means for movably supporting the said lock bar to permit the same to be moved to and from engaging position, actuating means for said lock bar moved by the cover when it moves, means interposed between the lock bar and said actuating means, including a striker member connected with the lock bar for actuating the same, means to normally hold the lock bar in locking position, the striker member being pivotally supported in position to be engaged by said actuating means to move the lock bar to disengaged position when the cover is raised, and means including a movable stop operably associated with said striker member and moved thereby into position to prevent lowering of the cover by engagement with the said actuating means.

2. In a stove, the combination of a plurality of burners and valves, a hinged cover to swing down over the burners, a locking bar having means for engaging and locking the valve to prevent their being opened, a spring for holding the locking bar in its locking position when the cover is down, cover-actuated means attached to the cover, a stop pawl, means connecting the same to the lock bar with means associated with the stop-pawl and located in the path of the cover-actuated means when the cover is being raised, and moved thereby for overcoming the spring and moving the locking bar to its unlocked position, said stop pawl operating to project into the path of the cover-actuated means when the cover starts to move down, for stopping the cover unless all the valves are closed, so as to permit the locking bar to move to its closed position.

3. In safety apparatus for preventing the clos-

ing of a stove cover over its burners if any burner is turned on, the combination of a plurality of handles corresponding respectively to the different burners for turning them on, a movable lock-bar common to all of said handles, said handles and said lock-bar having interlocking means, and said lock-bar normally resting in a locking position for preventing all the burners from being turned on, said interlocking means constructed so that if any handle is in its "on" position the lock-bar cannot move into its locking position, a hinged cover, control means located adjacent the hinged portion of the cover, actuated by the opening movement of the cover, with means connecting the same to said lock-bar for withdrawing the lock-bar from its locking position when the cover is raised to its open position; and means other than the lock-bar located adjacent the hinged portion of the cover, and associated with said control means for preventing the closing of the cover if any of the handles is in its "on" position.

4. In safety apparatus for preventing the closing of a stove cover over its burners if any burner is turned on, the combination of a plurality of handles corresponding respectively to the different burners for turning them on, a movable lock-bar common to all of said handles, said handles and said lock-bar having interlocking means, a spring normally holding the lock-bar in a locking position for preventing all the burners from being turned on, said interlocking means constructed so that if any handle is in its "on" position the lock-bar cannot move into its locking position, a hingedly mounted cover, control means actuated by the opening movement of the cover and connected to said lock-bar for withdrawing the lock-bar from its locking position when the cover is moved from its closed position to its open position; and means located adjacent the hinged portion of the cover, associated with said control means operating to obstruct the closing movement of the cover adjacent its hinged portion without imparting movement to the lock-bar if any of the handles is in its "on" position.

5. In safety apparatus for preventing the closing of a stove cover over its burners if any burner is turned on, the combination of a plurality of handles corresponding respectively to the different burners for turning them on, a movable lock-bar common to all of said handles, said handles and said lock-bar having interlocking means, and said lock-bar normally resting in a locking position for preventing all the burners from being turned on, said interlocking means constructed so that if any handle is in its "on" position the lock-bar cannot be returned to its locking position, a movably mounted cover, a striker arm connected to the cover so as to move when the cover is moved to its open position, control means actuated by the striker arm in the opening movement of the cover and connected to said lock-bar for withdrawing the lock-bar from its locking position, a movable stop connected with the control means and operating during the opening movement of the cover, to project itself into the path of the striker arm, and operating, if it is attempted to close the cover, to stop the same if any handle is in its "on" position, and a return spring for returning the control mechanism and the lock-bar when all of the handles are in a position to permit the return of the lock-bar, said spring also moving

the control means to pull the movable stop out of the path of the striker arm.

6. In safety apparatus for preventing the closing of a stove cover over its burners if any burner is turned on, the combination of a plurality of handles corresponding respectively to the different burners for turning them on, a movable lock-bar common to all of said handles, said handles and said lock-bar having interlocking means, and said lock-bar normally resting in a locking position for preventing all the burners from being turned on, said interlocking means constructed so that if any handle is in its "on" position the lock-bar cannot move into its locking position, a movably mounted cover, a striker arm connected to the cover so as to move when the cover is moved to its open position, including a striker-lever located in the path of movement of the striker arm when the cover is raised, a link connecting the striker-lever with the lock-bar for withdrawing the lock-bar from the handles to free them for turning "on," a stop-pawl connected with the striker-lever and operated thereby so as to be projected into the path of the striker arm to obstruct its return movement, thereby preventing the closing of the cover; and a spring associated with the striker-lever for pushing the lock-bar back into its locking position when all the handles have been turned to their "off" position, said spring also operating the control means to withdraw the stop-pawl from the path of the striker arm to permit the closing of the cover thereafter.

7. In safety apparatus for preventing the closing of a stove cover over its burners if any burner is turned on, the combination of a plurality of handles corresponding respectively to the different burners for turning them on, a movable lock-bar common to all of said handles, said handles and said lock bar having interlocking means, and said lock-bar normally resting in a locking position for preventing all the burners from being turned on, said interlocking means constructed so that if any handle is in its "on" position the lock-bar cannot be returned to its locking position, a movably mounted cover, a striker arm connected to the cover so as to move when the cover is moved to its open position, control means actuated by the striker arm in the opening movement of the cover and connected to said lock-bar for withdrawing the lock-bar from its locking position, a spring mounted so as to exert its force in a direction to return the lock-bar to its locking position, a pivoted stop connected to the control means and operating during the opening movement of the cover to be moved by the control means so as to project its end face into the path of the striker arm to stop the striker arm in the closing movement of the cover, and thereby obstruct the closing movement of the cover; the movement of the control means when the spring returns the lock-bar to its locking position, operating to withdraw the pivoted stop from the path of the striker arm to permit completion of the closing movement of the cover.

RICHARD BESOCKE.
